UNITED STATES PATENT OFFICE.

PEARL M. BIBB AND THEODOR LUDAT, OF MINDEN, WEST VIRGINIA.

PUMP-STRAINER.

1,231,477.

Specification of Letters Patent. Patented June 26, 1917.

Application filed September 8, 1916. Serial No. 119,071.

To all whom it may concern:

Be it known that we, PEARL M. BIBB and THEODOR LUDAT, citizens of the United States, residing at Minden, in the county of Fayette and State of West Virginia, have invented certain new and useful Improvements in Pump-Strainers; and we do hereby declare the following to be a full, clear, and exact description of the invention, such as will enable others skilled in the art to which it appertains to make and use the same.

This invention relates to new and useful improvements in pump strainers and the principal object of the invention is to provide a device providing a combination pump strainer and trap to remove trash and dirt from water entering the pump.

Another object of the invention is to provide a device from which the strainer may be readily removed in order that the same may be reversed and cleaned.

A further object of the invention is to provide a novel means for supporting the straining element in the device.

With these and other objects in view, the invention consists in the novel combination and arrangement of parts which will be fully set forth in the following specification and accompanying drawing, in which:—

Figure 1 is a view illustrating the device in use.

Fig. 2 is an enlarged longitudinal sectional view through the device, and

Fig. 3 is a detail view of the straining element.

Referring to the drawing 1 designates the well or hole from which the water is being pumped while 2 designates the pipe leading therefrom. This pipe 2 is fitted into the inlet side of the strainer designated generally by the numeral 3 and the outlet side of said strainer has fitted therein a pipe 4 which leads to the pump cylinder 5.

The strainer above referred to consists of a conical shell 6 having formed at its apex a hollow port 7 which is internally screw threaded to receive the nipple 8 which is in turn connected to drain valve 9 the opposite end of which is connected to the drain pipe 10. The shell 6 is formed near its base with the diametrically opposed internally screw threaded bosses 11 which communicate with the interior of the shell and arranged beneath one of the bosses and formed in the shell is a depression 12 the use of which will appear as the description proceeds. The

inlet pipe 2 is threaded into the boss 11 opposite the one under which the depression 12 is formed and the outlet pipe 4 is threaded into the boss opposite the one in which the pipe 2 extends.

A suitable cover 13 is provided for the base of the shell 6 and is held in place by suitable cap screws 14 which extend through the packing or gasket 15 and into the shell 6 so as to permit the cover to be easily removed. Formed on the cover at a point substantially centrally thereof and extending transversely of said cover is a downwardly extending flange or rib 17 provided at its lower terminal with the enlarged bead 18 the use of which will appear as the description proceeds.

The shell 6 is formed with a pair of inclined base flanges 19 which are positioned above the depression 12 as shown in the drawing and these flanges form supports for the strainer designated by the numeral 20 which consists of the frame 21 and the wire screen 22. The lower end of the frame is rounded as shown in the drawing and carries a depending extension 23 which is adapted to engage in the depression 12 so as to hold the lower edge of the strainer firmly in place. The side walls of the frame are slidable between the flanges 19 and the upper edge of the frame is provided with a groove so as to receive the bead 18 and form a tight joint to prevent the escape of any of the trash held out by the strainer around the edge thereof.

In order to further assist in the draining of the trash collected in the trap a suitable pet cock 24 is threaded into the cover 13 and is so arranged that upon the opening of the pet cock and of the valve 9 air will be admitted to the upper end of the trap thereby allowing the contents thereof to be readily withdrawn through the valve.

It will be apparent from the foregoing that when in use the inflowing liquid passes through the pipe 2 and is drawn against the strainer 20 and any foreign matter will be prevented from entering the pipe 4 and will settle into the bottom of the device. Upon stopping the pump and opening the valve 9 it will be evident that the liquid and the sediment contained within the strainer may be drawn off so as to keep the device free at all times. Should it be so desired the cover may be removed and the strainer taken out for repairs and cleaning and it

will be evident that upon slipping the same back in place and replacing the cover the strainer will be firmly held in position and the possibility of any of the foreign matter 5 passing into the pipe 4 around the edges of the strainer is eliminated due to the fact that the flanges 19 and the flange 17 form a tight joint between the strainer, the body and cover.

10 It will also be evident that when the pet cock 24 is opened the draining of the trap is facilitated.

While in the foregoing there has been shown and described the preferred embodiment of this invention, it is to be understood that such changes may be made in the combination and arrangement of parts as will fall within the spirit and scope of the appended claims.

20 What is claimed is:—

1. A device of the class described including an inverted conical body having an inlet and an outlet port near its upper end, flanges formed integral with the inner face 25 of the body near the outlet port, a strainer removably secured between the flanges, a cover for the body and a beaded rib extending transversely of the cover on its under face for engagement with the upper-edge of 30 the strainer to hold the same in place and prevent the escape of liquid around the edge thereof.

2. An inverted conical body having an inlet and an outlet port near its upper end, of flanges formed on the inner face of the body 35 near the outlet port, said flanges inclining downwardly, the body having a recess near its lower end arranged centrally of the flanges, a strainer adapted to slip between the flanges, an extension on the strainer 40 adapted to seat in the recess, the upper edge of the strainer being grooved, a cover for the body, a rib extending transversely of the cover centrally thereof and a bead on the lower edge of the rib for engagement in the 45 groove in the strainer to form a tight joint and prevent sediment from passing around the strainer and into the outlet pipe.

3. A trap including a body having inlet and outlet ports near its upper end, a strainer within the body between the inlet and outlet ports, the upper edge of the strainer being grooved, a cover for the body, and a transverse rib formed on the cover and engaging the walls of the groove to hold 50 the strainer in place and prevent the escape of liquid over the upper edge thereof.

In testimony whereof we affix our signatures in presence of two witnesses.

PEARL M. BIBB.
THEODOR LUDAT.
